CLAIM

The ornamental design for a digital inflator, as shown and described.

DESCRIPTION

FIG. 1 is a perspective view of a digital inflator showing our new design;

FIG. 2 is a front view thereof;

FIG. 3 is a rear view thereof;

FIG. 4 is a left side view thereof;

FIG. 5 is a right side view thereof;

FIG. 6 is an enlarge drawing of the top view thereof; and, FIG. 7 is an enlarge drawing of the bottom view thereof. The broken lines depict portions of the digital inflator that form no part of the claimed design.
